UNITED STATES PATENT OFFICE.

ERNEST L. ARTHUR AND ROBERT H. WORRELL, OF LESTER, WEST VIRGINIA.

METAL RAIL-TIE.

1,121,964.

Specification of Letters Patent. Patented Dec. 22, 1914.

Application filed April 20, 1914. Serial No. 833,206.

To all whom it may concern:

Be it known that we, ERNEST L. ARTHUR and ROBERT H. WORRELL, citizens of the United States, residing at Lester, in the 5 county of Raleigh and State of West Virginia, have invented certain new and useful Improvements in Metal Rail-Ties, of which the following is a specification.

The invention relates to new and useful 10 improvements in rail ties and has for one of its objects to provide a simple, durable and inexpensive rail tie which employs novel fastening means and will hold the rails firmly against spreading and creeping 15 and is preferably formed of metal.

Another object of our invention is to provide a metallic rail tie that is formed of a single piece of metal and is approximately concavo convex to provide a certain amount 20 of resiliency and to insure its remaining firm within the road bed.

Another important object of our invention is to provide novel means for securely 25 clamping the rails upon the tie, said means serving to securely hold the rails against creeping or spreading and dispensing with the usual spikes, thus eliminating the possibility of the rails working loose incident to the passing of trains thereover.

30 The above and additional objects are accomplished by such means as are illustrated in the accompanying drawings, described in the following specification and then more particularly pointed out as claimed.

35 With reference to the drawings, wherein we have illustrated the preferred embodiment of our invention as it is reduced to practice, and throughout the several views of which similar reference numerals designate 40 corresponding parts, Figure 1 is a plan view showing a rail in place and partly in section with the clamping means at one end of the tie removed. Fig. 2 is a fragmentary longitudinal sectional view, showing one 45 rail in secured position upon the tie. Fig. 3 is a transverse sectional view taken on the plane of line 3—3 of Fig. 2, and Fig. 4 is a detail perspective view of one of the pins forming a part of the rail clamping means.

50 Referring to the drawing by characters of reference the numeral 1 designates our improved rail tie and is formed of a single piece of some suitable metal and is approximately concavo convex. The ends of the tie 55 are enlarged and partly rounded to provide approximately spoon shaped end portions

2 and 3. These portions 2 and 3 are concavo-convex and may be readily tamped in the road bed and provide a great bearing surface at points where the most strain and weight is placed upon the tie. The body portion 4 of the tie is provided with inclined side walls 5. This arrangement in combination with the spoon shaped ends provides for a firm bearing of the tie upon 60 the road bed and prevents derangement. 65

We provide rail clamping means adjacent each end of the tie to securely clamp the rails. The rail clamping means comprises a rectangular plate 6 that is suitably secured 70 longitudinally of the tie adjacent each end thereof and provided at its ends with up-standing flanges 7. Keyhole slots 8 are formed adjacent each end of the plates and are positioned over depressions 9 formed 75 in the upper surface of the tie. Rail clamping members 10 and 11 are mounted upon each plate and are designed to clamp opposite sides of the rails 12, as clearly shown in Fig. 2. The rail clamping members 10 and 80 11 are formed of some suitable metal and are of suitable angular shape to conform to the shape of the rail and plates upon which they are mounted. To hold the clamping members 10 and 11 in clamping position we 85 provide in connection with each plate up-standing pins 13. The pins 13 are provided with transverse wedge shaped openings 14 adjacent their upper ends and at their inner ends are recessed upon opposite 90 sides to provide flat faces 15 and a head 16. To place the pins 13 in position the heads are inserted through the larger parts of the keyhole slots 8 so that the flat faces 15 may be positioned in the shank portions of the 95 slots thereof. This arrangement prevents turning of the pins and the depressions 9 formed in the tie permit the inserting of the pins as described.

The clamping members 10 and 11 are provided with transverse openings 16' extending therethrough from side to side and which are arranged to align with the openings 14 when the pins 13 are in position. Vertical openings or recesses 17 are formed 105 in the members 10 and 11 and receive the pins 13. The openings or recesses 17 extend partly through the members 10 and 11 and communicate with the transverse openings 16'.

Small wedge pins 18 are inserted through 110 the aligned openings 16' and 14 to hold the

clamping members 10 and 11 securely in position. The smaller ends of the pins 18 project beyond the members 10 and 11 and are preferably struck with a hammer so as to be bent, as at 19, to prevent accidental derangement. The under faces of the clamping members 10 and 11 are concaved, as at 20, to enable the ready positioning of the members upon the pins 13.

10 It will be readily seen with reference to the foregoing description and accompanying drawings that we provide a novel rail tie and clamping means for rails which will withstand the elements and serve in a reliable and efficient manner to hold the rails in position.

In practice, we have found that the form of our invention, illustrated in the drawings and referred to in the above description, as 20 the preferred embodiment, is the most efficient and practical; yet realizing that the conditions concurrent with the adoption of our device will necessarily vary, we desire to emphasize the fact that various minor 25 changes in details of construction, proportion and arrangement of parts may be resorted to, when required, without sacrificing any of the advantages of our invention, as set forth.

20 Having thus described the invention what is claimed as new, is:—

1. The combination with a rail tie, of rail clamping means carried by said rail tie and comprising plates having upstanding end 35 flanges mounted upon the tie adjacent to the ends thereof, said plates having keyhole slots

formed therein, said tie having depressions formed therein beneath the keyhole slots, upstanding pins having openings therethrough removably mounted within the keyhole slots, rail clamping members mounted upon said plates engaging the end flanges and provided with transverse openings alining with the openings in said pins, and wedge pins inserted through said openings. 45

2. The combination with a rail tie, of rail clamping means at each end thereof, said rail clamping means comprising clamping members to clamp opposite sides of rails and having openings formed transversely therethrough and vertical recesses communicating with said openings and opening at the lower sides of the members, upstanding pins carried by the tie having transverse openings adjacent their upper ends, said pins extending within said vertical recesses and having the openings therein alining with the transverse openings in the clamping members, wedge pins inserted through the alined openings and being bent at their smaller 60 ends, said upstanding pins having heads on their lower ends and plates to support the clamping members having key-hole slots therein to receive the pins. 55

In testimony whereof we affix our signatures in presence of two witnesses.

ERNEST L. ARTHUR.
ROBERT H. WORRELL.
